SEWING MACHINE

Charles F. Rubel and Albert M. Schweda, Chicago, Ill., assignors to Union Special Machine Company, Chicago, Ill., a corporation of Illinois

Application June 23, 1942, Serial No. 448,084

26 Claims. (Cl. 112—248)

This invention relates to an improved sewing machine construction and more particularly to one of the lockstitch type. It has reference especially to an improved form of rotary take-up for the needle thread of such a machine.

A primary object of the invention has been to provide a reliable and effective take-up mechanism of the rotary type which is of simple and inexpensive construction and is easy to use.

A feature of the invention in the attainment of the foregoing object is the provision of a take-up device for lockstitch machines, which is mounted upon a single shaft and has all of its thread-engaging elements operated at the same angular speed, corresponding with the reciprocations of the needle.

A further feature of the invention is the provision of two take-up elements secured to a single shaft and arranged to produce their take-up actions additively at certain times and subtractively at other portions of a cycle.

Still another feature of the invention is the provision of a pair of take-up elements on the same shaft, so constructed and arranged that one is adapted to engage the thread and impart its take-up action thereto only once during a complete cycle while the other is adapted to take up the thread twice during each cycle. The second element, moreover, is adapted to produce different take-up effects upon its two successive actions during a single cycle.

A still further feature is the provision of a take-up member having a camming action upon the thread, the contour of the cam being accurately developed to provide the correct take-up at all times. The form of the cam is such, furthermore, as to provide two take-up actions upon a single revolution. Moreover, the cam is so formed that a portion of its edge is arranged to produce a combined camming and lifting lever action upon the thread.

Toward the end of simplifying the use of the machine, the improved take-up has been so constructed that the elements which determine the path of the thread from the source of supply to the eye of the needle are readily accessible at all points and thus the threading operation is made easy to perform.

Other objects, features and advantages of the invention will appear from the detailed description of an illustrative form of the same which will now be given in conjunction with the accompanying drawings, in which:

Fig. I is a longitudinal, vertical section through the illustrative machine, taken along the line I—I

of Fig. VI, certain parts, however, being disclosed in side elevation.

Fig. II is a view partly in end elevation and partly in transverse section, illustrating the improved take-up mechanism in relation to the stitch-forming devices, certain parts of the construction being broken away to better illustrate the parts behind.

Fig. III is a transverse, vertical section through the needle head taken along the line III—III of Fig. I.

Fig. IV is a view similar to Fig. II illustrating the parts at a different stage in a cycle of operation.

Fig. V is a longitudinal, vertical section through the improved take-up mechanism and is taken along the line V—V of Fig. VI.

Fig. VI is a front elevation of the machine with a few parts broken away for purposes of better illustration of parts behind, the take-up devices being shown at a still later stage in their operation.

Fig. VII is a detail view partly in plan and partly in section along the line VII—VII of Fig. I, showing the take-up mechanism.

Fig. VIII is a view similar to Fig. II showing the parts in an even later stage in their operation.

Fig. IX is an enlarged detail view in section along the line IX—IX of Fig. XI, showing a portion of one of the take-up members.

Fig. X is a view similar to Fig. II showing the parts shifted to still another position, at a late stage in the cycle.

Fig. XI is a detail view in front elevation of the pair of take-up members, and

Fig. XII is a sectional view through the take-up members along the line XII—XII of Fig. XI.

The machine to which the improved take-up mechanism has been shown applied is in general of the type disclosed in the patent to Norman V. Christensen et al., No. 2,113,572 granted April 12, 1938. It has a frame including a work supporting bed 10 from one end of which rises a hollow, vertical standard 11 having at its upper end a laterally extending, hollow, overhanging arm 12. At the free end of the arm 12, which extends over the work support, there is provided a needle head 13 in which is mounted, for vertical reciprocation, a needle bar 14 carrying at its lower end one or more needles 15. The needle bar is reciprocated in suitable bearings by connections including a clamp collar 16 secured to the needle bar and carrying a pivot pin to which is connected a pitman 17 having its opposite end connected with a crank pin 18 carried at the end of a rotatable shaft 19. This shaft is journaled in bearings 20

and 21 and is driven by power supplied, in any suitable way and from any suitable source, to a combined hand wheel and pulley 22 secured to the outer end of the shaft 19, beyond the bearing 21. From the shaft 19 power is also delivered to complementary stitch-forming means and work feeding devices in the work supporting base. This is accomplished by means of a gear 23 secured to the shaft 19, an idler gear 24 mounted within the standard 11, and a gear 25 secured to the end of a shaft 26 which is mounted in suitable bearings beneath the work support and extends from the bottom of the hollow standard 11 to the forward end of the work supporting bed. A gear 27, secured to the shaft 26, meshes with a pinion 28 having only half as many teeth as the gear 27 so that the pinion 28 is driven at twice the angular velocity of the shaft 26. Pinion 28 is secured to a shaft 29 mounted in a bearing bushing 30 and carrying at its forward end the rotary component 20 of a rotary hook 31.

Any suitable feeding mechanism may be employed for advancing the work in proper relation to the stitch-forming devices. For example, the means disclosed in the patent to George Sauer et al., No. 2,035,508, granted March 31, 1936, may be employed. This includes a feed dog 32 secured to a feed bar 33 carried by a feed rocker 34 which may be reciprocated by suitable connections from the shaft 26 in the manner disclosed in said Sauer et al. patent. The lifting and lowering of the feed bar may also be accomplished in the manner disclosed in said patent. A presser foot 35, secured to the lower end of a presser bar 36, which is urged downwardly by a spring 37 (Fig. III), serves to urge the work yieldingly against the feed dog and the work supporting surface. The presser bar may be lifted against the action of the spring 37 by means of the lever 38 acting upon a block 39 slidable on the presser bar and which may be raised into engagement with a block 40 secured to the presser bar and then lifted further to raise the presser bar. An extension 41 of the block 39 carries a cam surface 42 (Fig. I) adapted to cooperate with a release pin 43 forming part of a thread tensioning device 44 around which the needle thread is passed, as will be explained more fully hereinafter. By the arrangement described, the thread tensioning device may be released, upon the camming of the release pin, as the presser bar is raised.

We come now to the improved take-up means for the needle thread loop. The requirements with respect to this take-up are set forth in the patent to Carl O. Nelson, No. 2,077,151, granted April 13, 1937. As explained in said patent, the take-up of the needle thread loop cast about the stationary component of a two-to-one type of rotary hook must be accomplished substantially during one half of its needle excursion or, in other words, during substantially 90° of the main shaft travel. This is accomplished by reciprocatory means in the construction disclosed in the Nelson patent. A primary purpose of the present invention has been to accomplish the same result by means of a rotary device having the features and advantages hereinabove pointed out. Various attempts have been made in the past to provide a rotary take-up for a lockstitch machine but for one reason or another these have not proved commercially satisfactory. In most instances, after having quickly taken up the needle thread loop in the available time, these prior devices have produced unnecessary slack thread

which has frequently become caught in the rotating parts, thus necessitating stoppage of the machine for re-threading and the like. Other devices have proved too complicated and expensive. In accordance with the present invention, the difficulties and objections encountered with prior rotary take-ups have been overcome and a simple, inexpensive and effective construction for providing the required take-up action, and the yielding of only sufficient slack at the appropriate times, has been provided.

There is secured to the shaft 19, between the bearing 20 and the arm carrying the eccentric pin 18, a gear 45 which meshes with a gear 46 secured to a take-up shaft 47. This shaft is journaled in a bushing 48 carried by a bulge 49 in the frame of the needle head. Oil holes 50 may be provided for the introduction of appropriate lubricant to the bushing 48. A collar 51 is secured by one or more set screws 52 to the shaft 47. This collar is provided with a radially extending flange 53 to which is secured, by means of screws 53a, a cam disc 54. The latter has the contour indicated in Fig. XI, which will be more fully discussed hereinafter. At its outer end the shaft 47 is provided with a radially extending flange 55 to which is secured a second take-up member 56. Screws 57 are provided for securing this take-up member to the flange 55. As will be seen, the relative positions of the members 54 and 56 may be varied as desired, to suit the particular requirements, by adjusting the angular position of the collar 51 on the shaft 47. Member 56 may suitably be composed of an inner disc element 58 and an outer annular element 59, the disc being secured to the end of the shaft by the screws 57, as before stated, and the annular element being attached to the disc by means of studs 60, which may, if desired, be provided with rollers. Two of these studs are provided in close relationship. Throughout the balance of the circumference of the two elements 58 and 59 the space between them is entirely open. The studs 60 may suitably be riveted to the disc 58 while the element 59 may be attached to the studs by means of screws 61 (Fig. IX). The surfaces of the studs or rollers are preferably grooved or of concave formation to facilitate proper engagement of the thread.

Cooperating with the cam member 54 is a plate 62. This has a longitudinal slot 63 through which the cam member extends during most of its rotation. Disposed at substantially a right angle to the main body of the plate is an integral portion 64 which is secured to the needle head by means of a pair of screws 65. The lower end 66 of the plate is bent outwardly at 90°, as shown in Fig. VIII, while the upper end 67 of the plate is preferably angled outwardly at only about 60°. At one end of the slot 63, at substantially the point at which the end 67 of the plate is bent outwardly, there is provided an eyelet 68 adapted to receive and guide the thread. At the opposite side of the slot 63, horizontally in line with the eyelet 68 and in the vertical plane of the grooved or concave portions of the studs 60 of the outer take-up member 56, there is provided a small opening 69 through the plate. Through this the thread may be passed for cooperation with the studs 60. A fixed stud 70, secured by a screw 71 to a bracket 72 attached by a screw 73 to the plate 62, has a groove 70a in one face in the plane of the grooves in the studs 60.

The course of the needle thread is as follows: It is led from a spool forming the source of sup-

ply to a pin 74 mounted on the top of the overhanging arm 12 above the standard 11 and from this it is led to an apertured guide 75 secured to the side of the needle head. After traversing several holes in this guide, the thread is passed around the thread tensioning device 44, over the check wire 76, forming part of the thread tensioning device, then under a pull-off arm 77 which is carried by the block 40 secured to the presser bar. Arm 77 passes through a slot in the side of the needle head which is of sufficient length to allow for the required movement of the presser bar. From the arm 77 the thread is led to and through the eyelet 68, across the face of the plate 62, inwardly through the opening 69 in the plate, around the forward stud 60 of the outer take-up member and, at times, across the groove of the pin 70, down to a fixed guide 78 on the front of the needle head, then through a guide 79 on the needle bar, through the eye of the needle down to and through the work.

The operation of the improved take-up devices described in the foregoing will now be explained in detail by reference to Figures II, IV, VI, VIII and X of the drawings. Assuming the parts of the machine to be in the positions indicated in Fig. II at the commencement of the cycle, it will be noted that the needle thread traverses its path of substantially minimum length between the pull-off arm 77 and the thread guide 78. This path will be as indicated above. Between the eyelet 68 and the opening 69 the thread will be deflected outwardly to only a slight extent by the cam member 54. At this time the thread crosses the edge of the cam at the point 54a (Fig. XI). The forward stud 60 is barely engaged with the thread and the latter passes over the fixed guide pin 70 in its course down to the guide 78. It will be understood that prior to reaching this position, the parts will have gone through a preceding cycle in which the needle will have been passed through the work and the loop thrown out by the needle upon its initial upward movement will have been engaged by the beak 31a of the rotary hook. Therefore, when the parts have reached the position indicated in Fig. II, the needle thread, after passing through the eye of the needle is extended downwardly through the work, around the back of the stationary bobbin case of the hook unit, upwardly from the beak 31a, and across the face of the stationary element of the hook to the point of connection with the fabric at the preceding stitch.

Now, as the take-up devices and the rotary hook continue their operation and advance from the Fig. II to the Fig. IV positions, only a very slight change in the action of the take-up devices will have occurred. The thread in passing from the eyelet 68 to the opening 69 will pass around a portion of the cam 54, which is of slightly less radius, but at the same time the leading stud 60 will have engaged the thread and increased its length slightly between the opening 69 and the stationary pin 70. In this portion of the cycle, therefore, the needle thread will have been yielded a very slight additional amount to enable the loop to carry over the full diameter of the bobbin case to the position indicated in Fig. IV.

In passing from the Fig. IV to the Fig. VI position, the slack in the needle thread, represented by the loop shown in Fig. IV, has been largely, though not completely, taken up, this being accomplished not only by the substantial increase in the path between the opening 69 and

the pin 70, by virtue of the advance of the stud 60, but also because of the added effect of the increasing diameter of the cam 54. The thread will at this time cooperate with a point on the cam designated 54b in Fig. XI, or possibly even a point between this and the point 54c.

As the cycle of the machine continues toward the Fig. VIII position of the parts, the take-up action will continue until the loop of the needle thread is drawn tightly against the under side of the work. This is accomplished by the continued movement of the forward stud 60 and the added effect of the further increase of the radius of the cam 54 up to the point 54c (Fig. XI). When the parts are in the Fig. VIII position, the thread will have been taken up to its maximum extent. In reaching this position, the needle thread will not only have been drawn tightly against the under side of the work, taking with it the adjacent portion of the bobbin thread, which will have been surrounded by the loop of the needle thread in the operation described, but to insure the proper take-up of the needle loop without danger of breaking the needle thread the latter in attaining the position of Fig. VIII will have depressed the checkwire 76 to a point substantially in line with the lower edge of the pull-off arm 77. Thus the check wire has disappeared in Fig. VIII. In reaching this position, moreover, it will be noted that the work has been advanced a stitch length, and the needle has descended a substantial distance toward the work, sliding its eye along the thread. Also, the hook beak 31a has gotten a substantial distance around on its idle revolution.

In proceeding from the Fig. VIII to the Fig. X position the rotary hook will complete its idle revolution while the needle will pass through the work and present a new loop to the loop engaging beak of the hook. During this interval between the Fig. VIII and Fig. X positions, there has been some demand for additional thread by the needle, this being about double the length of travel of the needle point from about $\frac{1}{4}$ inch above the work to its lowermost position of Fig. X. At the beginning of this portion of the cycle, there is a slight increase in the take-up action of the studs 60 but this is largely compensated by the decreasing radius of the part of cam 54 which is being traversed by the needle thread at this time. As shown in Fig. XI, this reduction in diameter of the cam commences at the point 54d and continues to the point 54e. The radius at the latter point is slightly less than the distance to the member 62 so that during an interval in the operation, the cam does not engage the thread. That part of the cycle in which the studs 60 and the cam 54 substantially counteract or offset each other begins toward the end of the movement from the Fig. VI position to the Fig. VIII position and continues for an arc of about 10 or 15° from the Fig. VIII position. During this period the needle is descending but simply slips its eye along the thread. However when the needle reaches a point about $\frac{1}{4}$ inch above the work support, which is approximately at the end of the period in the cycle above mentioned, the thread begins to move downwardly with the needle and then takes up a share of the thread yielded by the studs 60. As will be seen, the studs begin to yield the thread quite rapidly after they have passed below the horizontal plane through the axis of rotation of the take-up means. During this same period, the cam 54 begins to take-up the thread at a fairly rapid rate, this being just sufficient to prevent

the objectionable development of slack. Thus the net result of the thread yielding action of the member 56 and the take-up action of the cam 54 is to provide just the right amount of thread for the needle. At the beginning of this period, the point *e* on the cam will be passing adjacent the plate 62 and since the radius of the cam at this point is less than the distance from its axis to the surface of plate 62, the cam will at that moment have no effect upon the thread. The thread will simply lie flat across the surface of the plate from the eyelet 68 to the opening 69. However, during the latter part of the period in question, the thread will be engaged by the rising portion of the cam and will reach the point 54*f* (Fig. XI) by the time the Fig. X position is reached. During this latter portion of the movement from the Fig. VIII to the Fig. X position, the thread, in its course from the studs 60 to the guide 78, will engage and be deflected slightly by a stationary 20 guard member 80 (Figs. VI and VII). This also retards slightly the rate at which the thread is yielded by the studs 60.

Finally, upon continuing from the Fig. X position to the original Fig. II position, the studs 60 will yield the thread at a quite rapid rate. In fact, during the first part of this period the rollers will yield the thread more rapidly than it is required by the rotary hook. Accordingly, the enlarged end of the cam 54, which is active in the Fig. X position, will tend to lift the thread rapidly at this moment by a sort of leverage action in addition to the slightly increasing radius of the cam in this region. The leverage action tends to carry the loop substantially up to the angled portion 67 of the plate 62. This angled portion of the plate, however, prevents the loop from being carried frictionally, or otherwise, beyond its surface and serves to strip the thread from the cam. In the latter portion of the movement from the Fig. X to the Fig. II position, the loop engaged over the edge of the cam 54 will have passed over the high portion of the enlarged end of the latter and will have slid down the edge of the cam to a point of relatively small radius, as indicated in Fig. II. This occurs during the period in which the requirements of the rotary hook are at a maximum, since the major portion of the loop which encircles the bobbin case is formed at this time. The actions of the two take-up means (studs 60 and cam 54) are additively combined during this period to provide the necessary rapid release of the thread.

From the foregoing it will be clear that a very nice timing of the take-up and release actions of the two components of the rotary take-up is provided. The cam member 54 lends itself to very precise formation which brings about a proper additive effect, in relation to the studs 60, at certain times and a proper subtractive effect at other times. As a net result the two components insure the desired yielding of the needle thread at the required times and the desired firm take-up action on the thread in completing a stitch at the right times, without leaving any substantial slack in the thread at any time.

While an illustrative form of the invention has been described in considerable detail, it will be understood that numerous changes in the construction and arrangement of the several parts and in the general application of the invention may be made, without departing from its principles and scope. The terms and expressions used herein have been employed as terms of description and not of limitation.

We claim:

1. In a sewing machine having a thread carrying needle, means including a shaft for reciprocating said needle, take-up means for the needle thread comprising a single rotatable shaft driven by said first mentioned shaft and out of the vertical plane containing the latter, gearing connecting said shafts, a plurality of thread engaging members secured to said rotatable shaft and arranged to engage the thread at spaced points in different planes, said members being so constructed as to impart take-up actions of different character and frequency to said thread, and fixed guide means for constantly engaging the thread between the points of engagement by said members.

2. In a sewing machine having a thread carrying needle, means including a shaft for reciprocating said needle, take-up means for the needle thread comprising a single rotatable shaft driven by said first mentioned shaft and out of the vertical plane containing the latter, gearing connecting said shafts, and a plurality of thread engaging members secured in fixed relation to said rotatable shaft and arranged to engage the thread at spaced points, one of said members being arranged to provide a plurality of take-up actions and the other only a single take-up action of different character upon each revolution.

3. In a sewing machine having a thread carrying needle, means including a shaft for reciprocating said needle, take-up means for the needle thread comprising a single rotatable shaft driven by said first mentioned shaft and out of the vertical plane containing the latter, gearing connecting said shafts, and a plurality of thread engaging members secured in fixed relation to said rotatable shaft and arranged to engage the thread at spaced points, one of said members being arranged to provide a plurality of take-up actions upon each revolution, the operation and timing of said members being such that one of said take-up actions of said one member is arranged to combine with that of the other of said members, and another of said take-up actions is arranged to work in opposition to that of the other of said members.

4. In a sewing machine having a thread carrying needle, means including a shaft for reciprocating said needle, take-up means for the needle thread comprising a rotatable shaft driven by said first mentioned shaft, gearing connecting said shafts, and a plurality of thread engaging members secured to said rotatable shaft and arranged to engage said thread at a plurality of spaced points in its path to the needle, one of said members having a continuous cam edge arranged to engage the thread during the major portion of its rotation, and another of said members being so mounted in relation to said rotatable shaft as to be carried thereby through an orbital path in which it engages said thread and effects a take-up action thereon at a different timing from said one of said members.

5. In a sewing machine having a thread carrying needle, means including a shaft for reciprocating said needle, take-up means for the needle thread comprising a rotatable shaft driven by said first mentioned shaft, gearing connecting said shafts, and a plurality of thread engaging members secured to said driven shaft arranged to operate on said needle thread at spaced points, one of said members having a continuous cam edge arranged to engage the thread during the major portion of its rotation, said cam edge being so

formed as to impart a plurality of take-up actions to the thread with intermediate yielding of the thread upon each revolution of said member, and another of said members having thread engaging means arranged to impart only a single take-up action to the thread upon each revolution of said shaft.

6. In a sewing machine having a thread carrying needle, means for reciprocating said needle, and thread take-up means for the thread carried by said needle comprising a pair of rotary take-up members arranged to engage said thread at spaced points, one of said members having a continuous cam surface adapted to effect a take-up action in predetermined timing by forming a loop of varying dimension in said thread, and the other of said members having a thread engaging element which is carried through an orbital path to effect a differently timed take-up action.

7. In a sewing machine having a thread carrying needle, means for reciprocating said needle, and thread take-up means for the thread carried by said needle comprising a pair of rotary take-up members mounted on a single shaft and arranged to engage said thread at spaced points, one of said members having a continuous cam surface adapted to effect a take-up action in predetermined timing by forming a loop of varying dimension in said thread, and the other of said members having a thread engaging element which is carried through an orbital path to effect a differently timed take-up action.

8. In a sewing machine having a thread carrying needle, means for reciprocating said needle, and thread take-up means for the thread carried by said needle comprising a pair of synchronously driven rotary take-up members arranged to engage said thread at spaced points, a fixed guide arranged to engage said thread intermediate said spaced points, one of said members having a continuous cam surface surrounding the axis of rotation of said member adapted to form a loop of varying dimension in said thread, and one of said members being arranged to yield thread at times as it is taken up by the other of said members.

9. In a sewing machine having a thread carrying needle, means for reciprocating said needle, and thread take-up means for the thread carried by said needle comprising a pair of rotary take-up members arranged to engage said thread at spaced points, common driving means for rotating said members in synchronism, one of said members having a continuous cam surface adapted to form a loop of varying dimension in said thread, said cam surface being so formed as to cause said loop to increase and decrease in length twice upon each rotation thereof, and the other of said members being arranged to impart only a single take-up and a single yielding action upon each rotation.

10. A thread take-up for sewing machines which comprises a rotary unit having two thread-engaging members in different planes, one of said members having a substantially continuous cam surface arranged to engage a portion of the thread throughout the major part of its rotation and to form a loop of varying length, the other of said members being arranged in the course of its rotation to engage another portion of the thread with varying take-up action thereon, said members being so related as to combine their take-up actions additively during a portion of a

cycle and subtractively during another portion of the cycle.

11. A thread take-up for sewing machines which comprises a rotary unit having two thread-engaging members in different planes, one of said members having a substantially continuous cam surface arranged to engage a portion of the thread throughout the major part of its rotation and to form a loop of varying length, the other of said members being arranged in the course of its rotation to engage another portion of the thread with varying take-up action thereon, said one of said members having two cam lobes one of which combines its effective additively and the other subtractively in relation to the take-up action of said other of said members.

12. A thread take-up for sewing machines which comprises a shaft, a rotary member secured to said shaft, said member having its outer edge of varying radius with respect to said shaft, a fixed plate adjacent said member having a slot through which the edge of said member extends, said plate being provided with means for guiding a thread and directing the same transversely across said slot, said member upon rotation of said shaft engaging said thread and projecting a loop of varying length from the face of said plate, and a thread engaging element rotatable with said member about the axis thereof on a radius less than the minimum effective radius of said member, one of said guiding means serving to direct the thread into the path of said element.

13. A thread take-up for sewing machines which comprises a shaft, a rotary member secured to said shaft, said member having its outer edge of varying radius with respect to said shaft, a fixed plate adjacent said member having a slot through which the edge of said member extends, said plate being provided with means for guiding a thread and directing the same transversely across said slot, said member upon rotation of said shaft engaging said thread and projecting a loop of varying length from the face of said plate, the form of said member being such as to increase and decrease the length of said loop twice upon each revolution, the upper end of said plate being bent outwardly in the path of said loop along a more nearly radial line and serving to strip the same from the edge of said member as the maximum take-up action is attained.

14. In a machine of the class described a thread carrying needle, means for reciprocating the same, a rotary hook operated at twice the frequency of said needle arranged to cooperate with the needle thread, take-up means for said needle thread comprising a single rotary unit, and means for driving said unit at the same frequency as said needle, said unit having a thread engaging element carried in an orbital path and a second element having a substantially continuous thread engaging surface of varying radius from the axis of rotation of said unit.

15. In a machine of the class described a thread carrying needle, means for reciprocating the same, a rotary hook operated at twice the frequency of said needle arranged to cooperate with the needle thread, take-up means for said needle thread comprising a single rotary unit, means for driving said unit at the same frequency as said needle, said unit having a thread engaging element carried in an orbital path and a second element having a substantially continuous thread engaging surface of varying radius from the axis

of rotation of said unit, and fixed guide means for engaging said thread both in advance of and beyond the point of engagement thereof by said second element.

16. In a machine of the class described a thread carrying needle, means for reciprocating the same, a rotary hook operated at twice the frequency of said needle arranged to cooperate with the needle thread, take-up means for said needle thread comprising a single rotary unit, means for driving said unit at the same frequency as said needle, said unit having a thread engaging element carried in an orbital path and a second element having a substantially continuous thread engaging surface of varying radius from the axis of rotation of said unit and fixed guide means in the plane of said orbital path adapted to engage the thread both in advance of and beyond the point of engagement thereof by said first mentioned element.

17. In a machine of the class described a thread carrying needle, means for reciprocating the same, a rotary hook operated at twice the frequency of said needle arranged to cooperate with the needle thread, take-up means for said needle thread comprising a single rotary unit, means for driving said unit at the same frequency as said needle, said unit having a thread engaging element carried in an orbital path and a second element having a substantially continuous thread engaging surface of varying radius from the axis of rotation of said unit and fixed guide means arranged to engage said thread at points in advance of, beyond, and intermediate of the points of engagement thereof by said elements.

18. A thread take-up for sewing machines which comprises a shaft, a rotary member secured to said shaft, said member having its outer edge of varying radius with respect to said shaft, fixed thread guiding means at opposite sides of said member, the outer edge of said member being so formed as to provide both a camming action and a lifting lever action upon the thread in the course of rotation of said member, and means for stripping the thread from said member at a predetermined point, and a thread engaging element mounted for orbital movement adjacent said member upon rotation of the latter, one of said fixed guiding means serving to direct the thread into the path of said element.

19. In a sewing machine having a thread carrying needle, means for reciprocating said needle, and thread take-up means for the thread carried by said needle comprising a pair of rotary take-up members arranged to engage said thread at spaced points, fixed guide means arranged to engage said thread at each side of one of said members, and fixed guide means arranged to engage the thread alternately in advance of and beyond the point of engagement thereof by the other of said members in the passage of the thread from said one of said members to the needle.

20. In a sewing machine having stitch forming mechanism including a reciprocable needle, a co-operating rotary hook and means for actuating said stitch forming mechanism in timed relation but at different frequencies, needle thread take-up means comprising a plurality of rotatable thread manipulating elements disposed and arranged to engage the needle thread in series relation, one of said elements taking up the thread at the frequency of the needle and another of said elements taking up the thread at the frequency of the rotary hook, and means for rotating said elements at the same angular speed.

21. In a sewing machine having stitch forming mechanism including a reciprocable needle, a co-operating rotary hook and means for actuating said stitch forming mechanism in timed relation but at different frequencies, needle thread take-up means comprising a plurality of rotatable thread manipulating elements disposed and arranged to engage the needle thread in series relation, one of said elements taking up the thread at the frequency of the needle and another of said elements taking up the thread at the frequency of the rotary hook, and means for rotating said elements at a uniform and the same angular speed.

22. In a sewing machine having stitch forming mechanism including a reciprocable needle, a complementary stitch forming member operating at a different frequency than the needle and means for actuating said needle and stitch forming member in timed relation, needle thread take-up means comprising a plurality of thread manipulating elements rotatable about a common axis and disposed and arranged to engage the needle thread in series relation, guide means associated with said elements for retaining the thread in proper relation thereto, at least one of said elements having a camming action on the thread and the associated guide means being arranged to cause engagement of the thread with said one of said elements substantially constantly during its rotation and means for rotating all of said elements at the frequency of the needle.

23. In a sewing machine having stitch forming mechanism including a reciprocable needle, a complementary stitch forming member operating at a different frequency than the needle and means for actuating said needle and stitch forming member in timed relation, needle thread take-up means comprising a plurality of thread manipulating elements rotatable about a common axis and disposed and arranged to engage the needle thread in series relation, and means for rotating all of said elements at the frequency of the needle, one of said elements being so formed as to impart a take-up action to the thread at the frequency of the needle and the other at the frequency of said complementary stitch forming member.

24. In a sewing machine, a thread take-up device comprising a plurality of rotatable thread engaging members, one of said members having a peripheral thread engaging surface arranged to provide a camming action on the thread and another having an orbitally moving element and thread guiding means constructed and arranged to lead a thread through the respective zones of action of said members; the direction of travel of said thread through the zone of action of said one of said members being generally parallel with the axis about which said member rotates, and the direction of travel of said thread through the zone of action of said other of said members being generally transverse to the axis about which said last named member rotates.

25. In a sewing machine, a thread take-up device comprising a plurality of rotatable thread engaging members, means for rotating said members at the same angular speed, and thread guiding means for leading a thread through the respective zones of action of said members, said members and thread guiding means being so constructed and arranged that said thread is directed through the zone of action of one of said members in a direction generally parallel with the axis about which said member is rotated for

camming engagement thereby, and said thread is directed through the zone of action of another of said members in a direction generally transverse to the axis about which said last named member rotates for engagement thereby.

26. In a sewing machine, a thread take-up device comprising a plurality of coaxially arranged, rotatable thread engaging members, means for rotating said members synchronously, and thread guiding means for leading a thread through the respective zones of action of said members, said members and thread guiding means being so con-

structed and arranged that said thread is directed through the zone of action of one of said members in a direction generally parallel with the axis of rotation of said members for camming engagement by one of said members and said thread is directed through the zone of action of another of said members in a direction generally transverse to said axis for engagement by said other of said members.
